CLAIM

The ornamental design for an adapting piece for stack installation of an LED display screen, as shown and described.

DESCRIPTION

FIG. 1 is a front upper perspective view of an adapting piece for stack installation of an LED display screen showing my design;

FIG. 2 is a side elevation view thereof;

FIG. 3 is an opposite side elevation view thereof;

FIG. 4 is a back end elevation view thereof;

FIG. 5 is a front end elevation view thereof;

FIG. 6 is a top plan view thereof;

FIG. 7 is a bottom plan view thereof; and,

FIG. 8 is an upper front perspective view thereof, shown in an alternate position and an environment of use.

The broken lines in FIG. 8 illustrate the environment of the claimed design and form no part thereof.

1 Claim, 4 Drawing Sheets
